UNITED STATES PATENT OFFICE.

MATTHEW W. INGRAHAM, OF GLACE BAY, NOVA SCOTIA, CANADA.

SPRING BED-BOTTOM.

No. 839,293.

Specification of Letters Patent.

Patented Dec. 25, 1906.

Application filed August 30, 1906. Serial No. 332,656.

To all whom it may concern:

Be it known that I, MATTHEW W. INGRAHAM, a subject of the King of England, residing at Glace Bay, in the Province of Nova Scotia, Dominion of Canada, have invented 5 a new and useful Bed Spring-Bottom, of which the following is a specification.

This invention has relation to spring-bottoms for beds; and it consists in the novel 10 construction and arrangement of parts, as hereinafter shown and described.

The object of the invention is to provide a device adapted to be easily and readily operated for taking up the slack bulging tension 15 of bed-springs.

The device consists, primarily, of a bar to which one end of the spring is attached, and which in turn is adapted to be connected with the bed-posts. To the other end of said 20 spring a similar bar is attached, but which is mounted to slide longitudinally of guides carried by a third bar. The last said bar is provided with means for attachment with the opposite bed-posts. A screw is journaled in the last said bar and passes through 25 the perforation in the intermediate bar and engages a thread provided in a collar located at the middle of a yoke which bears at its upper ends upon said intermediate bar.

30 In the accompanying drawings, Figure 1 is a bottom view of the bed-spring. Fig. 2 is a side elevation of the same.

The device comprises a bar 1, which is provided with hooks 2, which are adapted to 35 pass around either the head or foot bed-posts. The said bar 1 rests at its ends upon said rails of the bed. One end of the bed-spring 3 is attached to the bar 4. The bar 5 is provided with the hooks 6, which are 40 adapted to pass around the posts at the opposite end of the bed from the posts engaged by the hooks 2. The guide-pins 7 7 are attached to the bar 5 and pass through perforations in the bar 4. The said bar 4 is

adapted to move longitudinally of the said 45 pins 7 7. The yoke 8 bears at its ends against the side of the bar 4. The said yoke 8 is provided at its middle with an internal-threaded collar 9. A screw 10 is journaled in the bar 5 and passes through a perforation 50 11, provided in the bar 4, and the threaded end of said screw engages the thread of the collar 9.

From the above description it is obvious that as the screw 10 is rotated the bar 4 will 55 be drawn toward or moved away from the bar 5, according to the direction in which the said screw 10 is rotated. When the bar 4 is turned toward the bar 5, the slack of the 60 spring 3 is taken up and the tension of the said spring is increased. The reverse is the case when the bar 4 is moved away from the bar 5.

Having described my invention, what I claim as new, and desire to secure by Letters 65 Patent, is—

A bed-spring comprising bars, means attached to said bars for fixing the same at opposite ends of the bed-frame, a spring attached to one end of one of said bars, a movable bar located intermediate of the first said bars and being attached to the opposite end of said spring, guides carried by the bar unattached to the spring and engaging the said movable bar, a yoke bearing at its ends 70 against the said movable bar adjacent said guides and having at its middle an internally-threaded collar, a screw journaled to the bar unattached to the spring and engaging the thread of the collar of said yoke. 75 80

In testimony that I claim the foregoing as my own I have hereto affixed my signature in the presence of two witnesses.

MATTHEW W. INGRAHAM.
